UNITED STATES PATENT OFFICE.

ALVAH D. HADSEL, OF WILKES-BARRE, PENNSYLVANIA.

CONCRETE-MIXER.

No. 909,784.

Specification of Letters Patent.

Patented Jan. 12, 1909.

Application filed September 5, 1908. Serial No. 451,782.

To all whom it may concern:

Be it known that I, ALVAH D. HADSEL, a citizen of the United States, residing at Wilkes-Barre, in the county of Luzerne and State of Pennsylvania, have invented certain new and useful Improvements in Concrete-Mixers, of which the following is a specification.

This invention relates to concrete mixing machines, and has particular reference to that type of these machines known as rotating, batch, non-tilting machines.

Among the several objects aimed at in this invention are to improve the general construction of the machines whereby a more rapid and thorough mixing of the concrete is effected, to increase the durability of the machine, to provide a maximum strength of construction proportionate to the weight of material employed and yet to provide for ready repair of any parts which may become disabled, to secure the greatest ease of operation thereby requiring a minimum amount of horse power for operating purposes, and other advantages which will hereinafter more fully appear.

For a full understanding of the invention, including its construction and characteristic advantages, reference is to be had to the following detail description and the accompanying drawings, in which—

Figure 1 is a general perspective view of the invention; Fig. 2 is a vertical transverse section through the mixing drum, parts being broken away; Fig. 3 is a detail perspective of one of the drum paddles and one of the deflecting brace members attached thereto; Fig. 4 is a detail perspective of one of the drum face plates; Fig. 5 is a broken sectional view of one of the end plate rings, and Fig. 6 is a detail sectional view indicating one of the bearing supports for the drum.

Throughout the following detail description, and on the several figures of the drawings, similar parts are referred to by like reference characters.

By reference to Fig. 1 it will be noted that this invention comprises generally speaking a frame 10 mounted in any convenient manner on truck wheels, whereby the device may be supported or transported from place to place. The drum 11 is of peculiar form and construction, and is mounted for rotation upon rollers journaled in suitable bearings upon the frame 10. The

drum 11 is of general prismatic form and comprises a plurality of similar rectangular flat face plates 13, illustrated especially in Fig. 4. As therein shown each of said plates 13 includes as integral parts thereof lateral flanges 14 extending at right angles from the body of the plate, end flanges 15 extending from the flat portion of the plate at obtuse angles, and a central longitudinal toothed gear segment 16. The several flanges and also the flat portion of the plate are provided with a plurality of holes for attachment purposes, as will hereinafter fully appear. The face plates 13 are attached each to each at their oblique flanges 15, rivets or like fastening means being passed through the holes therein for this purpose.

As illustrated in the drawings the drum 75 is of octagonal form, but it will be understood that the precise number of faces may be varied if desired. When the face plates are thus connected together the several gear segments 16 constitute in effect a continuous 80 gear wheel with which a driving pinion 17 is in permanent mesh. The power pinion 17 it will be understood will be driven from the engine 18 in a conventional manner.

The ends of the drum consist of polygonal 85 plates 19, each of which will have as many edges as there are face plates 13, and to said end plates the lateral plate flanges 14 will be secured by means such as rivets passing through the holes thereof. Each end plate 90 19 is provided with a central opening, one for the purpose of receiving the material therethrough into the drum and the other for the purpose of discharging the material. Surrounding each of said openings and secured rigidly in any suitable manner to the end plate is a heavy rigid flaring ring 20. Each of said rings comprises a body portion 95 from which extends a flat attachment flange 21 for connection to the end plate 19, and extending at an angle from said body portion inwardly is a flaring flange 22. As indicated in Fig. 2 it will be apparent that said rings constitute not only reinforcing means for the end plate openings, but also serve to prevent the material from the interior of the drum from spilling or splashing outwardly through said openings, which would be undesirable.

Since the drum is filled and emptied along the line of its axis of rotation it is essential that supporting means for the drum be pro-

vided outside of said axis. The supporting means for the drum in this instance comprises a rigid annulus 23 secured concentrically upon the outer surface of each end plate 5 and a plurality of rollers 24 journaled beneath the central axis of the drum upon supports journaled upon the frame 10. As illustrated each annulus consists of a body portion having a concave periphery and an 10 inwardly projecting flange 23', whereby the same is secured to its end plate. The rollers 24 complementally are convex for coöperation with the concave periphery of the annuluses 23. By this construction several important advantages are accomplished. Each 15 annulus constitutes a means whereby any material which may be scattered during the operation of dumping materials into the drum, for instance, will be deflected from the rollers, and a further advantage lies in the fact that for any ordinary wear there may possibly be upon the bearing surfaces between the drum and the rollers, the drum 20 will always be supported in such a manner as to prevent any lateral movement with respect to the supporting rollers, a matter of 25 importance in machines of this type which are driven by a single toothed gear wheel. A serious defect heretofore existing in machines of this general class consists in the 30 fact that the drums may shift laterally, causing breakage of the gear teeth.

The face plates 13 as well as the other parts of the construction may be made of any suitable materials. It has been found, however, that the face plates are preferably to be made of heavy cast iron and the end plates should be of plate steel.

Thus far described the drum is well 40 adapted for mixing purposes, due to the prismatic form thereof, but for the purpose of increasing the efficiency of the mixing drum and also to facilitate the discharge of materials therefrom, it is desirable to employ upon the interior thereof a series of 45 lifting and mixing devices. As illustrated particularly in Figs. 2 and 3 said devices consist essentially of a plurality of paddles 25, each consisting of a scoop portion 26 and a lateral extension 27. The paddle is provided with a flange 28 at one end for attachment to one end plate, and the extension 27 extends from the longitudinal axis of the body portion at an angle and is attached 50 securely to the opposite end plate by means of a flange 29. The extension 27 constitutes a means for directing materials toward and into the scoop portion 26, during the rotation of the drum. It will be understood 55 that the preferred number of paddles will be equal to the number of face plates 13 and that a paddle will be secured to each of said plates. Each paddle will preferably be constructed of a single blank of sheet metal. A 60 series of deflecting brace members or bars 30

are provided, each of said members extending from the bottom of a scoop portion 26 of one paddle to the lateral extension of the next paddle. As indicated each member 30 is riveted directly to said scoop portion 26 and is connected to the extension of the next by means of a connecting arm 31. The members 30 are spaced from their respective face plates and extend at an angle to the lateral extensions to which they are connected. Not only do these members serve as bracing devices for the interior structure but also for the purpose of deflecting the materials toward that end of the drum away from which the lateral extensions 27 deflect the same. It will be seen therefore that the materials will be given a zigzag reciprocating motion from one end of the drum to the other, thus enhancing the mixing qualities of the machine. By reference to Fig. 2 it will be noted that the scoop portions of the 70 paddles are located substantially at one end of the drum, whereby the discharge of the materials will be materially facilitated.

Any convenient form of discharge spout 90 may be employed, but that herein illustrated comprises a chute 32 which is supported from the frame 33 exterior to the drum. For this purpose a pair of links or rods 34 are connected to the upper end of the frame 95 33 and to the outer end of the chute 32. As an illustration of a convenient means for supporting the chute 32 in its discharging position as illustrated, or for holding it in its outer position during the mixing operation 100 of the drum, there is indicated a hook 35 connected at one end to the frame 33 and detachably connected to the chute. It is to be understood that the form of the discharging means may be varied to a great extent 105 within the scope of the invention. As shown in Fig. 2 the mixed materials being lifted by the scoop portions of the paddles will be dropped upon the receiving or inner end of the chute 32. Inasmuch as the scoop portions 26 are located substantially at one end of the drum, the chute 32 need not be so long as is usual in devices of this character. It will of course be understood that the flaring rings 20, being attached permanently 110 to the drum ends, will not have frictional contact with the chute 32 nor receiving spout 36 secured to any suitable support.

It is to be understood that the several details of construction may be varied within 120 the scope of this invention and without departing from the spirit thereof as set forth in the claims hereinafter made.

Having thus described the invention, what is claimed as new, is:

1. The herein-described concrete mixer comprising a rotary drum consisting of rectangular metal face plates each of which has integral side and end flanges, means to secure the side flanges of adjacent plates to 130

gether, end plates of polygonal form, means to secure the end plates to the end flanges of the face plates, the respective sides of the end plates coinciding with the said face plates, each of the said end plates having a central opening, heavy metallic rings surrounding said openings and secured to the plates and each having an inwardly projecting flare, means for supporting said drum and means for rotating the same.

2. In a device of the character set forth, a mixer drum section consisting of a cast metal rectangular plate having integral side and end flanges, the end flanges being at an oblique angle to the said plate, and a central longitudinal integral gear segment extending between said side flanges.

3. In a concrete mixer, the combination with a drum comprising a plurality of similar rectangular face plates, a pair of polygonal end plates to the respective sides of which the several face plates are secured, and a paddle secured to the inner surface of each face plate and to both end plates, of reinforcing and supporting means therefor comprising an annulus having a concave outer periphery secured to the outer face of each

end plate and a plurality of convex rollers coöperating with each annulus.

4. In combination, a concrete mixer drum 30 comprising a plurality of rectangular face plates, each having an integral gear segment intermediate of its sides, and a pair of polygonal end plates secured to the said face plates, a supporting and reinforcing annulus 35 secured concentrically to the outer face of each end plate and having a concave outer periphery, rollers having convex peripheries coöperating with said annuluses, and means coöperating with said gear segments to rotate the drum.

5. In a concrete mixer, the combination with a drum having an end plate with a central opening therethrough, of a heavy annulus surrounding said opening, said annulus 45 having a flat flange secured to the end plate and a flaring deflecting flange extending inwardly within the drum.

In testimony whereof I affix my signature in presence of two witnesses.

ALVAH D. HADSEL.
